BERTRAND L. PREMO, OF IRVINGTON, NEW JERSEY.

CASE FOR CIGARETTES OR THE LIKE.

1,187,513.

Specification of Letters Patent. Patented June 20, 1916.

Application filed June 27, 1914. Serial No. 847,635.

To all whom it may concern:

Be it known that I, WILLIAM E. EDWARDS, a citizen of the United States, and a resident of Irvington, in the county of Essex 5 and State of New Jersey, have invented certain new and useful Improvements in Cases for Cigarettes or the like, of which the following is a specification.

This invention relates to that class of 10 cases which are made up in silver and other suitable or ornamental materials to hold cigarettes and be carried in the smoker's pocket.

The objects of the invention are to provide 15 an improved case of this character; to hold a supporting rack centrally between the hinged body portions and resiliently retain cigarettes upon the supporting plate, both by the same springs; to provide means 20 for holding the rack centrally which can be employed to hold cards or the like in the body portions of the case; to secure simplicity of construction and operation, without liability to get out of order or break, 25 and to obtain other advantages and results as may be brought out in the following description.

Referring to the accompanying drawing, in which like numerals of reference indicate 30 the same parts throughout the several views, Figure 1 is a perspective view of my improved case showing the same open and one of the retaining arms of the supporting rack drawn back; Fig. 2 is a sectional view 35 on line A—A of Fig. 1 looking in the direction indicated by the arrows, and Fig. 3 is a sectional view on line B—B of Fig. 2 looking in the direction of the arrows.

In the specific embodiment of the invention illustrated in said drawings, the reference numeral 1 indicates a casing of any desired configuration adapted to the purpose, preferably comprising body portions 2 and 3 hinged to each other as at 4 and 45 adapted to close together as is usual. It is to be understood that the said body portions provide bezels 5, 6, respectively, adapted to meet and engage when the case is closed and that the portions are dished or 50 hollowed away from each other to provide an interior chamber. Means are also preferably provided, such as a spring catch 7 at the end of one of the body portions away from the hinge adapted to engage the other

portion, to hold the two together until 55 manually released.

Within the chamber formed by the hinged body portions 2, 3 is a supporting rack 8 having means such as tongues 9, 9 at one end to pivotally mount it upon the line 60 of hinging of the two body portions, preferably upon the same hinge pin. I have shown this rack consisting of a plate 10 and upon opposite faces of this plate are hinged retaining arms 11, 11 for resiliently engaging 65 cigarettes or the like and holding them by pressing them toward the said plate 10. Preferably said retaining arms are pivoted near the bottom or pivoted edge of the plate 10 parallel to the line of hinging thereof, 70 and this hinging I have shown effected by a hinge pin 12 supported by bosses 13, 13 near the opposite side edges of the middle plate 10 for each of the retaining arms. The lower edge of each of the retaining arms receives 75 this hinge pin, said edge being cut away centrally so as to expose the middle portion of the hinge pin, and upon this exposed portion of each hinge pin is a helical spring 14 the end of which engages the arm 80 to normally force it toward the supporting plate 10. The other end of this spring 14 presses against the adjacent body portion and thus tends to force the supporting rack away from that body portion. Inasmuch as 85 there is another spring acting in the same manner upon the other body portion of the case, the supporting rack will obviously assume a central position between said body portion at all times. 90

In order to form a neat and efficient contact between the springs 14 and body portions, I pivot a lever 15 upon each of the hinge pins 12, said lever extending longitudinally of the casing and bearing against 95 a middle portion thereof. The spring 14 engages this lever 15 at its inner end, as shown, and normally holds the body portions open, so that when the catch 7 is released the body portions open apart into 100 the position shown in the drawings. The retaining arms 11, 11 may be swung away from the middle plate 10, see Fig. 1, and cigarettes placed between the same, as will be readily understood, the same springs 105 serving for resiliently holding the supporting rack in central position and the retaining arms against the middle plate 10 of the

rack. Preferably the retaining arms 11 are near their free ends substantially the width of the supporting plate 10 so as to engage all the cigarettes upon said plate, and obviously these retaining arms may be of any suitable length in the other direction. The supporting plate itself preferably has at its side edges transverse strips 16, 16 secured thereto so as to form flanges at both sides of the plate which serve as stops for the cigarettes. It will also be understood that the plate 10 and arms 11 can be made of any suitable configuration, and although I have shown them cut into ornamental open work, this is not essential to the invention.

The levers 15 afford convenient retainers for cards, photographs or small memorandum slips which it may be desired to slip beneath them so as to be held flat against the inner surface of the body portions.

Other detail modifications may be made in manufacturing my improved case without departing from the spirit and scope of the invention, and I do not wish to be understood as limiting myself except as required by the following claims when construed in the light of the prior art.

Having thus described the invention, what I claim is:—

1. In a case of the character described, hinged body portions adapted to close together and open apart, a supporting rack pivoted between said body portions on the line of hinging thereof, members hinged to opposite sides of said supporting rack adjacent to its pivoting to the body portions and adapted to engage the said body portions, and springs on the hinge pins of said members for normally forcing them against the body portions.

2. In a case of the character described, hinged body portions adapted to close together and open apart, a supporting rack pivoted between said body portions on the line of hinging thereof, levers hinged at their inner ends to said supporting rack adjacent to its pivoting to the body portions, and springs on the hinge pins of said levers for normally forcing their outer ends against the body portions.

3. In a case of the character described, hinged body portions adapted to close together and open apart, a pivoted supporting rack adapted to be inclosed by said body portions, levers carried by said supporting rack engaging said body portions at a distance from their hinging, and springs pressing against said levers and normally holding said supporting rack centrally between said body portions.

4. In a case of the character described, hinged body portions adapted to close together and open apart, a supporting rack pivoted between said body portions on the

line of hinging thereof, retaining arms hinged to opposite sides of said supporting rack adjacent its pivoting to the body portions, and springs at opposite sides of the supporting rack each resiliently acting upon one of the body portions and the adjacent retaining arm, whereby the said springs serve both to close the retaining arms toward the supporting rack and to hold the supporting rack centrally between the body portions.

5. In a case of the character described, hinged body portions adapted to close together and open apart, a pivoted supporting rack having a plate between said body portions, retaining arms on opposite sides of said supporting plate, and means at opposite sides of the supporting rack each resiliently pressing against one of the body portions and the adjacent retaining arm, whereby the said means operate both to close the retaining arms toward the supporting rack and to hold the supporting rack centrally between the body portions.

6. In a case of the character described, hinged body portions adapted to close together and open apart, a hinged supporting rack having a plate adapted to be inclosed by said body portions, means pivoted on said supporting plate for retaining cigarettes thereon, levers carried by said supporting plate engaging said body portions, and springs pressing against said levers and retaining means and normally holding the supporting rack centrally between the body portions.

7. In a case of the character described, hinged body portions adapted to close together and open apart, a hinged supporting rack having a plate adapted to be inclosed by said body portions, hinged arms on said supporting plate for retaining cigarettes thereon, levers carried by said supporting plate engaging the body portions, and springs pressing against said levers and retaining arms and normally holding said supporting rack centrally between the body portions and causing the retaining arms to normally engage the cigarettes.

8. In a case of the character described, hinged body portions adapted to close together and open apart, a supporting rack hinged between said body portions and having a plate adapted to lie therebetween, retaining arms on opposite sides of said plate hinged thereto adjacent its hinged end, and springs upon the same hinge pins with said retaining arms each having one end acting upon one of the hinged body portions and its other end engaging one of said retaining arms so as to close said arms against the supporting plate and hold the rack central with respect to the body portion.

9. In a case of the character described, the combination of hinged body portions, a

supporting rack hinged between said body portions and having a plate, retaining arms on opposite sides of said plate hinged thereto adjacent its hinged end, levers upon the 5 same hinge pins with said retaining arms adapted to lie against the body portions, and springs on said hinge pins adapted to force said levers and retaining arms apart so as

to hold the retaining arms against the supporting plate or cigarettes thereon and also 10 hold the supporting rack central with respect to the body portion.
